UNITED STATES PATENT OFFICE.

MOSES F. CARR, OF LEXINGTON, MASSACHUSETTS, ASSIGNOR TO CARR FASTENER COMPANY, OF CAMBRIDGE, MASSACHUSETTS, A CORPORATION OF MAINE.

FASTENER.

Application filed June 14, 1924. Serial No. 719,927.

This invention aims to provide an improved stud and socket fastener.

In the drawings, which illustrate a preferred embodiment of my invention:—

5 Fig. 1 is a front elevation of the preferred form of my invention;

Fig. 2 is a rear elevation of the stud;

Fig. 3 is a section partly in elevation on the line 3—3 of Fig. 1;

10 Fig. 4 is a section similar to Fig. 3, but showing the locking means disengaged from the socket-engaging part of the stud;

Fig. 5 is a front elevation of the preferred form of socket; and

15 Fig. 6 is a section on the line 6—6 of Fig. 4.

Referring to the drawings and to the preferred form of my invention selected for illustrative purposes, I have shown a stud

20 adapted to be secured to a curtain 7 in any suitable manner, but I prefer, as illustrated, to provide a front plate 9 presenting a plurality of attaching prongs 11, which pass through the curtain 7 and openings in the

25 base 13 of a resilient socket-engaging member 15. The prongs are then clenched into depressions 17 provided in the base 13 of the stud so as to present a smooth surface at the back of the curtain, as best illustrated in

30 Figs. 2, 3 and 4. By this method of attaching the stud to the curtain, the parts are reduced to a minimum in number because of the elimination of the usual back plate or clench plate. Thus the cost of manufacture

35 of a fastener of this type is substantially reduced without reducing the durability and the fabric-gripping qualities of the stud.

The socket-engaging part of the stud is provided with slots 19 which extend to the base 13 of the stud, thereby to permit contraction and expansion of the socket-engaging part when engaging or disengaging a socket. This socket-engaging member 15 is also provided with an annular depression or neck 21 for engagement with a socket.

45 While the stud may be maintained in engagement with a socket by the resiliency of the contractile and expansible member 15, I prefer to provide means for locking the head with the socket and means for displacing the locking means to permit contraction of the member 15. The above-mentioned means preferably comprises a pull-button

member 25 presenting a shouldered locking part 23 for engagement with the inside surface of the neck 21 and when engaged therewith to prevent contraction of the head of the stud, and an enlarged button or knob 29 located outside of the front plate 9. 55

The knob 29 may be manually operated to 60 shift the shouldered part 23 into or out of engagement with the neck 21 as desired.

The shouldered locking part 23 is preferably made separate from the rest of the pull-button member and riveted thereto after the 65 reduced part of the pull-button member has been entered through the aperture in the front plate 9. Thus the front plate 9 and pull-button member 25 are held in assembled relation to each other as a unit before assembling the stud upon the stud-carrying curtain 7. 70

The preferred form of socket includes an attaching screw 31 having a hexagonal head 35 rigidly secured to the hexagonal body portion 37 of the socket. The preferred method of securing the head of the screw to the body portion of the socket is to provide an enlarged portion 38 at the inner end of the socket body portion 37 into which the head 35 of the attaching screw fits, and in which it is secured by rolling a part of the enlarged portion 38 over the edge of the head of the screw and onto the face thereof. 75

The socket also includes a front plate 39 which is secured to the flange 41 located at the outer end of the body portion 37, and presents a stud-receiving aperture surrounded by an annular neck-engaging wall 42 preferably curved inwardly from the face of 80 the front plate 39 to provide a smooth bearing surface for the socket-engaging part 15. 85

Inside the socket, I have provided a sealing and tool-receiving part 43 also hexagonal in cross-section to fit the body portion 37. 90 This part 43 present a hexagonal depression 45, for reception of a suitable socket-attaching tool, and is normally urged into aperture-closing position by a spring 47. 95

The socket may be secured in place upon the body 49 of an automobile by inserting a suitable tool in the depression 45 in the sealing and tool-receiving part 43 and rotating the tool in a clockwise direction, thus rotating the entire socket and screw 31 to draw 100 the body portion 37 of the socket into a re- 105

cess 51 in the body 49 until the flange at the outer end of the socket is seated against the face of the automobile body 49.

When the socket is attached to the body 5 of the car, that portion of the front plate 39 which is clenched over the flange 41 will be seated against the face of the body of the car, or other object, and will, as illustrated, conceal the recess in the body of the car 10 from view, thus presenting a socket that is substantially flush with the surface of the object to which it is attached.

When engaging the stud with the socket, the locking shoulder part 23 must be out of engagement with the neck of the stud so that the head of the stud may contract and enter the stud-receiving aperture. The neck then engages the peripheral wall 42 of the stud-receiving aperture, thus allowing the 20 head to expand again and thereafter the locking shoulder part 23 may be urged into locking engagement with the neck of the stud by pressing inwardly upon the knob 29 located at the front side of the curtain. 25 When the stud is locked with the socket, it cannot be separated therefrom by any accidental strain exerted upon the curtain in any direction because of the locking shoulder which prevents contraction of the head of 30 the stud.

Separation of the stud from the socket is effected by pulling upon the knob 29 until the head of the stud is free from the socket or by pulling the knob to disengage the 35 locking shoulder and thereafter exerting a slight pull on the lower edge of the curtain.

While I have shown and described a preferred form of one embodiment of my invention, it will be understood that changes 40 involving omission, substitution, alteration and reversal of parts, and even changes in the mode of operation, may be made without departing from the scope of my invention, which is best defined in the following 45 claims.

I claim—

1. A separable fastener comprising, in combination, a socket presenting a stud-receiving aperture surrounded by a stud-receiving wall, a cooperating stud presenting a resilient socket-engaging member having an annular depression for engagement with said wall, a locking member carried within said resilient socket-engaging member for 50 engagement with the inner wall of said depression to prevent contraction of said resilient member when said stud and socket are engaged, and a pull button member connected with said locking member and presenting a button at the outer face of the 55 stud opposite the resilient socket-engaging end of the stud for shifting said locking

member out of engagement with the inner face of said depression to permit separation of the stud and socket. 65

2. A separable fastener comprising, in combination, a socket presenting a stud-receiving aperture surrounded by a generally curved wall, a cooperating stud presenting a resilient socket-engaging portion having a 70 neck for cooperative engagement with said wall, a neck-engaging locking part carried by said stud for direct contact with the inner face of said neck to expand said neck against the wall of said stud-receiving aperture to 75 lock said stud and socket together, a manually operable push and pull button member forming part of the fastener assembly for operating said locking part, and an attaching plate spaced away from said socket-engaging portion to provide a space into which 80 said locking part may be moved to permit contraction of said socket-engaging portion.

3. A socket for a stud and socket fastener including a casing presenting a stud-receiving aperture, a spring-pressed sealing disc normally closing said aperture, tool-receiving means located in said sealing disc, and attaching means for securing said casing to a support when said sealing disc is turned 90 by means of a tool engaged with said tool-receiving means. 85

4. A socket for a stud and socket fastener including a casing presenting an attaching screw at one end of said casing and a stud-receiving aperture at the opposite end, a spring-pressed sealing disc normally closing said aperture and tool-receiving means located in said sealing disc for reception of 95 a tool to attach said socket to a support. 100

5. A socket for a stud and socket fastener including a casing presenting an attaching screw at one end of said casing and a stud-receiving aperture at the opposite end, a spring-pressed sealing disc non-rotative relative to said casing and normally closing said aperture and tool-receiving means located in 105 said sealing disc for reception of a tool to attach said socket to a support.

6. A socket for a stud and socket fastener including a casing, an attaching screw presented at the inner end of said casing, a stud-receiving aperture presented at the outer end of said casing and tool-receiving means normally closing said aperture, said tool-receiving means non-rotative relative to said attaching screw thereby producing relative rotation of said attaching screw when a tool is engaged with said tool-receiving means and thereafter rotated. 110

In testimony whereof, I have signed my name to this specification. 115

MOSES F. CARR.
